UNITED STATES PATENT OFFICE.

WALTER F. HICKS, OF LEOMINSTER, MASSACHUSETTS.

DESIGN FOR A BOW-CLASP.

43,926.

Specification for Design.

Patented Apr. 29, 1913.

Application filed February 17, 1913. Serial No. 749,046. Term of patent 14 years.

To all whom it may concern:

Be it known that I, WALTER F. HICKS, a citizen of the United States, residing at Leominster, in the county of Worcester and State of Massachusetts, have invented a new, original, and ornamental Design for a Bow-Clasp, of which the following is a specification, reference being had to the accompanying drawings, forming part thereof, in which—

Figure 1 is a plan of a bow clasp showing my new design; Fig. 2 is a side view, and Fig. 3 is an end view.

I claim:

The ornamental design for a bow clasp as shown.

WALTER F. HICKS.
